DESIGN FOR A VANITY CASE

Ruth Warner Mason, Passaic, N. J.

Application February 10, 1940, Serial No. 90,182

Term of patent 3½ years

To all whom it may concern:

Be it known that I, Ruth Warner Mason, a citizen of the United States, residing at Passaic, county of Passaic and State of New Jersey, have invented a new, original, and ornamental Design for Vanity Cases, of which the following is a specification, reference being had to the accompanying drawing, forming a part thereof.

In the drawing:

Fig. 1 is a front elevational view of a vanity case in closed position showing my new design;

Fig. 2 is a side elevational view thereof, and

Fig. 3 is a front elevational view thereof with the case in open position.

I claim:

The ornamental design for a vanity case, substantially as shown.

RUTH WARNER MASON.
